(57) **CLAIM**

The ornamental design for a photo printer, as shown.

DESCRIPTION

FIG. 1 is a right front perspective view of the photo printer comprising the present invention;

FIG. 2 is a front elevation view thereof;

FIG. 3 is a right side elevation view thereof;

FIG. 4 is a left side elevation view thereof;

FIG. 5 is a back elevation view thereof; and,

FIG. 6 is a top plan view thereof.

The broken lines are for illustrative purposes only and form no part of the claimed design.
